PATENTED JAN. 6, 1903.

T. KING.

PERMUTATION PADLOCK.

APPLICATION FILED AUG. 6, 1902.

NO MODEL.

UNITED STATES PATENT OFFICE.

THOMAS KING, OF GLENCOE, MICHIGAN.

PERMUTATION-PADLOCK.

SPECIFICATION forming part of Letters Patent No. 717,867, dated January 6, 1903.

Application filed August 6, 1902. Serial No. 118,600. (No model.)

To all whom it may concern:

Be it known that I, THOMAS KING, a citizen of the United States, and a resident of Glen-
5 coe, in the county of Huron and State of Michigan, have invented a new and Improved Per-
mutation-Padlock, of which the following is a full, clear, and exact description.

This invention relates to a class of padlocks having rotatable locking-rings that by adjustment secure the inserted leg of a bowed shackle-bar within the lock-body and by a proper change of adjustment release the shackle-bar, permitting its withdrawal from the locking-rings.

15 The object of my invention is to provide novel features of construction for a permutation-padlock that are simple, easy to manufacture, and convenient to manipulate, affording a very secure lock at a moderate cost.

20 The invention consists in the novel construction and combination of parts, as is hereinafter described, and defined in the appended claims.

Reference is to be had to the accompanying 25 drawings, forming a part of this specification, in which similar characters of reference indicate corresponding parts in all the figures.

Figure 1 is a side view of the complete lock. Fig. 2 is a sectional side view taken through 30 the axis of the lock, substantially on the line 2 2 in Fig. 3, showing the shackle-bar in locked condition. Fig. 3 is a sectional plan view substantially on the line 3 3 in Fig. 2. Fig. 4 is a similar view taken substantially on the line 4 4 in Fig. 2. Fig. 5 is a detached side elevation of the base-plate and keeper-posts erected thereon. Fig. 6 is a plan view of the details shown in Fig. 5. Fig. 7 is a sectional side view of the lock with parts adjusted to 40 release the shackle-bolt; and Fig. 8 is a plan view, partly in section, on the line 8 8 in Fig. 7.

The base-plate 10 of the lock-body is peripherally circular, and at a proper distance 45 from its outer edge a circular boss 10^a is formed or secured thereon, the defining edge of the boss being concentric with the periphery of the base-plate. A pivot-shaft 11 is erected at the center of the base-plate and 50 boss thereon, said shaft being in the form of a flat-headed bolt, having a screw-thread

formed on the normal lower end, as at *a*, this threaded portion having threaded engagement within a tapped perforation in the center of the base-plate 10, as clearly shown in 55 Figs. 2 and 7. Upon the boss 10^a four similar keeper-posts 12 are erected, are evenly spaced apart, and positioned at the circular edge of the boss, each having at its upper end a dowel-pin *b*.

A plurality of rings 13 are provided of similar exterior diameter to that of the base-plate 10, said rings of equal thickness having proper clearance from the side of the posts 12. Each ring 13 is annularly recessed in its upper face, 65 these similar recesses *c* having sufficient depth and diameter to permit the insertion into each recessed ring of a detent-ring 14, each furnished with an inwardly-projecting annular rib or flange *d*.

The detent-rings 14 have projections *g* formed on their outer edges, any preferred number of these projections being produced on each detent-ring, the projections being preferably V-shaped, the series of spaced projections for each detent-ring having a loose-seated engagement in V-shaped notches formed in the side wall of the recesses *c*, whereby each detent-ring is adapted for a rotatable adjustment in each main ring 13, by 70 removing the detent-ring, turning it a portion of a revolution, and again seating it within the recess *c* at a desired point, which permits the projections or teeth *g* to enter the notches.

Between each pair of adjacent main rings 13 and detent-rings 14 a spacing-disk 15 is introduced, said disks each having four equally-spaced openings *h* therein, that are at such a distance from the circular edge 90 thereof as permits the free insertion of the four posts 12 therethrough, such engagement of the disks and posts disposing the edges of the disks in the same plane with the peripheries of the main ring 13.

It will be seen that the inner circular edges of the flanges *d* on the detent-rings 14 are of less thickness than the bodies of said detent-rings and have their lower edges flush with the lower faces of the body portions 14, which 100 construction affords an annular rabbet on the inner upper corner of each detent-ring, hav-

ing a depth equal to half the thickness of said ring, as is clearly shown in Figs. 2 and 7. Furthermore, it will be noticed that the inner edges of the flanges *d* have a loose contact with the convex outer surfaces of the post 12, so that the main rings 13 are disposed concentric with the central shaft 11 when the latter is in place. A cap-plate 16 is provided having a central aperture for the reception 10 of the body of the shaft 11 and also having four socket-indentations formed in the lower side thereof for the reception of the dowel-pins *b*, which by their engagement with the cap-plate hold the plate from turning on the 15 shaft.

The disks 15 are centrally perforated to receive the shaft 11 and when in position between adjacent main rings 13 are held stationary by the posts 12.

20 The shackle-bar 17, constituting the hasp of the padlock, is provided with a long member or leg 17^a and a short leg 17^b, these members being spaced apart and held in parallel planes by the bow portion of the shackle-bar, 25 which is preferably jointed, as at 17^a, and in service is disposed exterior to the cap-plate 16. The legs 17^a 17^b of the shackle-bar are preferably cylindrical in their bodies, and upon the outer portion of the longer leg 17^a 30 a suitable number of locking-toes *i* are formed or secured. The toes *i* equal in number the annular spaces that intervene the annular flanges *d* and are designed to fit loosely between said flanges. Two diametrically opposite notches *k* are formed in the flanges *d* 35 on each detent-ring 14, and in these opposite notches the toes *i* are adapted to slide downward when said notches are vertically aligned in opposite rows.

40 As shown in Fig. 2, the shorter leg 17^b extends downward of a length sufficient to permit it to pass through the cap-plate 16 and uppermost main ring 13, said cap-plate having two diametrically opposite orifices *m* 45 therein, that are notched to permit the free passage of two spaced toes *i*, that project outwardly from the body of the shorter leg 17^b.

The spacing-disks 15 are of like construction, preferably thinner than the rings 13, 50 and, as shown in Fig. 4, are each provided with two diametrically opposite orifices *n*, having notches *n'* in their edges, similar to the notched orifices *m* in the cap-plate 16, and it is apparent that these orifices *n* and notches 55 *n'* will, if correctly formed in the disks between the apertures through which the posts 12 pass, be vertically aligned in two sets that are in registry with the orifices *m* in the cap-plate 16, so that the shackle-bar may be 60 freely passed downward through the disks 15 and detent-rings 14 when the notches *k* are aligned with the notches *n'*.

The pivot-shaft 11 is fitted to pass neatly down through a central perforation in the 65 cap-plate 16, and, as shown in Figs. 2 and 7, is provided with a thin circular edged head 16^a, cross-kerfed, as at *f*, for the use of a

screw-driver to screw the lower end of the shaft into the base-plate 10, and, as represented in Figs. 2 and 7, two lateral notches *o* 70 are formed on the legs of the shackle-bar 17, where enlargements 17^c are formed on the exterior portions of the legs 17^a 17^b, said notches receiving the peripheral edge of the head 16^a and holding the shaft from upward 75 movement when the shackle-bar is fully inserted and secured by adjustment of the rings 13, as will presently be explained.

Upon the exterior of the main rings 13 80 evenly-spaced shallow grooves *p* are preferably formed, that may be vertically alined in rows, and on each ring 13, between said grooves *p*, individual designating characters—such for example, as letters of the alphabet—are formed. As a feature of advantage 85 the designating-letters of the alphabet are preferably indented in the surface of the rings 13 and coated with illuminating-paint, so that the letters may be readily distinguished in the dark when it is necessary to 90 adjust the lock, thus dispensing with other light at night to enable an opening of the padlock.

The spaced letters on each main ring 13 95 may form numerous combinations to be read in vertical lines, and for security but one letter on each ring should be directly opposite a notch *k* in the detent-ring 14, that is seated and detachably locked to the main ring, so that when these letters are alined the shackle-bar 17 may be inserted and withdrawn, providing the main rings are not rotatably moved, such a movement after the shackle-bar is fully inserted obviously serving to remove one or more of the notches *k* from alinement with others that may be properly alined, and thus effect a locking of the shackle-bar within the body of the lock by preventing its upward movement.

By provision of the changeable detent-rings 110 14 and means to rotatably adjust said detent-rings on respective main rings 13 numerous combinations may be effected to bring into service other designating-letters that are on the main rings, and as these combinations 115 may be effected readily the lock may be set for locking and opening on a different combination frequently, thus insuring security from tampering with it.

In order to prevent a complete removal of 120 the shackle-bar from the body of the lock, a check-pin *r* is inserted transversely through the lower end of the longer leg 17^a of the shackle-bar, so that it projects therefrom and produces a lateral abutment on the inner side 125 of the shackle-bar leg 17^a.

A notch *n*² is formed opposite each notch *n'* in the respective disks 15, and as these disks are held from turning by the posts 12 it will be seen that these notches *n*² will afford 130 a free passage for the inner end of the check-pin *r* therethrough. No notch is formed in the cap-plate 16 for the check-pin *r* to pass through. Consequently said pin will impinge

upon the cap-plate when the shackle-bar 17 is moved to draw it from the lock-body composed of the rings 13 and disks 15, as indicated by dotted lines in Fig. 2, and this will prevent the complete withdrawal of the leg 17^a, while the short leg 17^b is removed sufficiently from the cap-plate to afford space between its free end and the cap-plate for the release of a hasp-staple or the like, that may have been engaged with the bow end of the shackle-bar.

To afford room for the lower end of the longer leg of the shackle-bar to receive proper depression and accommodate the check-pin 15 *r*, so that it may be disposed in the detent-ring 14 that is adjacent to the boss 10^a on the base-plate 10, a recess *n*⁴ of proper form is produced in said boss immediately below the orifices *n* in the disks 15, so that the lower extremity of the shackle-bar leg 17^a may be seated therein and properly dispose the toes *i* between the flanges *d* on the detent-rings 14 when the shackle-bar 17 is fully inserted within the body of the padlock.

25 I have shown and described the disks 15 as all provided with notches *n*⁴ in both orifices *n*. As a matter of fact this provision is not absolutely necessary, except for the top disk 15, that is engaged by both of the shackle-bar legs 17^a 17^b; but in the manufacture of these parts of the lock in quantity it is of advantage to have the disks all formed alike, which will facilitate the assembling of the details of the lock, as any of the disks will 35 be available for the uppermost one in the lock-body.

The formation of the joint 17^d in the shackle-bar 17 greatly facilitates the engagement of said portion of the lock with a staple 40 that is of such diameter as to nearly fill the bow portion of the bar, and is a valuable feature of the invention.

Having thus described my invention, I claim as new and desire to secure by Letters 45 Patent—

1. A permutation-lock, comprising a base-plate, a plurality of posts erected on the base-plate equally distant from its center, a series of rings having indicating characters on their peripheries and held free to rotate on the posts, a perforated cap-plate engaging the upper ends of the posts and held from rotation thereby, a shackle-bar having two legs that loosely engage perforations of the cap-plate and pass through the rings, lateral spaced toes on the shackle-bar legs adapted for locked engagement with the rings, and a

pivot-shaft holding the cap-plate and series of rings together.

2. A permutation - padlock, comprising a 60 base-plate, four posts erected from the base-plate equally distant from its center and from each other, a series of main rings having indicating characters on their peripheries, a detent-ring seated in a recess in each main ring 65 and changeably secured thereto, each detent-ring having an annular flange projected inwardly therefrom, a perforated cap-plate engaged by the upper ends of the posts and held from rotation thereby, a central shaft 70 screwing into the base-plate, a series of disks perforated to slide upon the posts and upon the central shaft, said disks spacing apart the main rings, a bowed shackle-bar having two legs whereon spaced toes are laterally 75 formed, said legs passing through perforations in the cap-plate, the disks having notched orifices for the passage of said legs and toes therethrough, the annular flanges having notches through which the toes pass, and 80 spaces between the flanges receiving the toes and permitting the rotation of the main rings on the posts to lock and release the shackle-bar.

3. A permutation - padlock, comprising a 85 base-plate, a series of main rings, a corresponding series of detent-rings, each seated in a recess formed in one of the main rings, said detent-rings each having a series of peripheral projections that changeably interlock within 90 notches formed in the peripheral wall of the recess occupied by the detent-ring, a bowed shackle-bar having a long leg and a short leg, a series of spacing-disks held from rotation by posts erected on the base-plate, said posts 95 at their upper ends entering sockets in the cap-plate, the spacing-disks having notched orifices, a series of spaced toes on the legs of the shackle-bar working between the detent-rings and adapted to pass through the notched orifices in the disks, and a flat-headed pivot-shaft passing through the cap-plate between the legs of the shackle-bar, the head of the shaft engaging its edge with notches in the legs of the shackle-bar which prevents the 105 displacement of the shaft when the shackle-bar is locked.

In testimony whereof I have signed my name to this specification in the presence of two subscribing witnesses.

THOMAS KING.
